CLAIM

I claim the ornamental design for clip on Galilean binocular magnifier, as shown and described.

DESCRIPTION

FIG. 1 is a perspective view of a clip on Galilean binocular magnifier according to an embodiment of the invention.

FIG. 2 is a front elevational view of the clip on Galilean binocular magnifier of FIG. 1.

FIG. 3 is a back elevational view of the clip on Galilean binocular magnifier of FIG. 1.

FIG. 4 is top plan view of the clip on Galilean binocular magnifier of FIG. 1.

FIG. 5 is a bottom plan view of the clip on Galilean binocular magnifier of FIG. 1.

FIG. 6 is a side elevational view of the clip on Galilean binocular magnifier of FIG. 1; and,

FIG. 7 is another side elevational view of the clip on Galilean binocular magnifier of FIG. 1.

Items shown in broken lines are for illustrative purposes only and form no part of the claimed invention. The broken lines depict portions of the clip-on Galilean binocular magnifier that form no part of the claimed design. Those broken lines representing the clip depict environment only and form no part of the claimed design.
